US00D562982S

(12) **United States Design Patent** (10) **Patent No.:** **US D562,982 S**
(45) **Date of Patent:** **** Feb. 26, 2008**

(54) **BIOPSY PUNCH**

(75) Inventor: **Stephen J. Sullivan**, Redmond, WA
(US)

(73) Assignee: **Gynex Corporation**, Redmond, WA
(US)

(**) Term: **14 Years**

(21) Appl. No.: **29/270,500**

(22) Filed: **Dec. 22, 2006**

(51) **LOC (8) Cl.** **24-02**

(52) **U.S. Cl.** **D24/147**

(58) **Field of Classification Search** **D24/130, D24/133, 146, 147, 143, 144, 148, 145, 138; 606/167, 184, 205–208, 139, 112–150**

See application file for complete search history.

(74) *Attorney, Agent, or Firm*—Black Lowe & Graham, PLLC

(57) **CLAIM**

The ornamental design for biopsy punch, as shown and described.

DESCRIPTION

FIG. 1 is a perspective view showing my new design;

FIG. 2 is a top view thereof;

FIG. 3 is a left side view thereof;

FIG. 4 is a right side view thereof;

FIG. 5 is a bottom view thereof;

FIG. 6 is a rear view thereof, the left side view being a mirror image of the right side view; and,

FIG. 7 is a front view thereof.

The broken lines in FIGS. 1–7 are shown for illustrative purposes only and form no part of the claimed design.
